UNITED STATES PATENT OFFICE.

ROBERT MORROW, OF KANSAS CITY, MISSOURI.

TURN-BUTTON.

1,176,975.

Specification of Letters Patent. Patented Mar. 28, 1916.

Application filed May 22, 1915. Serial No. 29,882.

To all whom it may concern:

Be it known that I, ROBERT MORROW, a citizen of the United States, residing at Kansas City, in the county of Jackson and State of Missouri, have invented a certain new and useful Improvement in Turn-Buttons, of which the following is a specification.

My invention relates to improvements in turn-buttons.

It is particularly adapted for use in fastening grain doors for cars.

The object of my invention is to provide a turn-button of novel construction which may be readily adjusted so as to project different distances, when in the locking position, so as to accommodate it to door frames of different widths between the jambs.

Another object of my invention is to provide novel means for releasably locking the button against longitudinal movement when in the locking position.

The novel features of my invention are hereinafter fully described and claimed.

In the accompanying drawings which illustrate the preferred embodiment of my invention, Figure 1 is an elevation of a door frame equipped with my improved turn-buttons. In this view one of the buttons is shown unlocked and the others are shown in the locked positions. Fig. 2 is a vertical section on the line 2—2 of Fig. 1. Fig. 3 is an enlarged elevation, partly broken away, of my improved locking device shown fastened in the locking position by a piece of wire, a portion of a grain door and a door frame being shown. Fig. 4 is an enlarged horizontal section on the line 4—4 of Fig. 1.

Similar reference characters designate similar parts in the different views.

1 designates the turn-button comprising, preferably, a flat plate or bar having a central longitudinal slot 2 through which extends a securing device or support comprising a screw 3. The screw 3 extends through a plate 4, which at opposite ends is provided respectively with two inwardly turned flanges 5, the inner edges of which are adapted to rest against the outer side of a cleat 6 which is secured to the outer side of a door member 7, which, in grain cars may be one of a plurality of boards disposed one above the other, and which rest against the inner sides of two vertical strips 8 secured respectively to the inner sides of the jambs 9, of which they form parts.

The upper and lower edges of the turn-button 1 are respectively provided with notches 10 adapted to respectively receive the flanges 5 when the button is in the locking position, shown in Fig. 3, at which time the button has one end overlapping the outer side of the adjacent strip 8. By adjusting the button 1 longitudinally on the screw 3, the flanges 5 may be caused to enter different pairs of the notches 10, thus holding the button from longitudinal movement when in the locking position, and permitting the button to project different distances beyond the edge of the door member 7 to suit door frames of different widths between the jambs 9. The plate 4 may be secured to the cleat 6 by two screws 11.

In applying the invention to the members of a grain door, each door member 7 has secured to its outer side adjacent to its respective ends, two cleats 6 to which are respectively secured two of the locking devices, as shown in Fig. 1.

In the operation of the invention, a door member 7 is applied to the inner sides of the strips 8, the buttons 1 carried by the member being disposed in the unlocked vertical position occupied by the upper left hand button in Fig. 1. The buttons are then longitudinally adjusted on the screws 3 to the positions suitable for obtaining the desired overlap on the strips 8, after which they are turned to the locking positions, in which the flanges 5 will enter the notches 10 respectively adjacent thereto. The buttons will thus be held from longitudinal movement, and the door members 7 will be securely held in place. For releasably holding the buttons from being accidentally turned so as to be released from the flanges 5, each button may be provided with an ear 12, Fig. 3, provided with a hole 13 through which may be inserted a piece of wire 14 which is also extended through a hole 15 in an ear 16 provided on the plate 4, the ends of the wire being twisted together as shown. To permit the buttons 1 to assume the horizontal locked position, the plates 4 may be disposed obliquely, so that the flanges 5 at opposite ends of the plates 4 will be respectively above and below the upper and lower edges of the buttons, as shown.

While I have illustrated and described my invention, applied to a grain door, it is obvious that it may be applied to various other devices to which turn-buttons are applicable.

I do not limit my invention to the structure shown and described, as modifications, within the scope of the appended claims, may be made without departing from the 5 spirit of my invention.

What I claim is:

1. A turn button, a support on which the button is pivoted and longitudinally adjustable, means for releasably locking the button against longitudinal movement when it has been turned to a pre-determined position, and releasable means for holding the button from disengagement with said locking means.
- 10 2. A turn button, a support on which the button is pivoted and longitudinally adjustable, means for releasably locking the button against longitudinal movement from either of two positions to which it may be adjusted, and releasable means for holding the button from disengagement with said locking means.
- 15 3. A turn button provided with a notch, a support on which the button is pivoted and longitudinally adjustable, a locking device adapted to enter said notch for holding the button against longitudinal movement when it has been turned to a pre-determined position, and releasable means for holding the button from disengagement with said locking device.
- 20 4. A turn button provided with a longitudinal slot, and a notch, a support in said slot on which the turn button is pivoted and longitudinally slidable, and a locking device adapted to enter said notch and hold the button against longitudinal movement when the button has been longitudinally adjusted to a pre-determined position and has 25 been turned to the locking position.
- 25 5. A turn button provided with a longitudinal slot and a plurality of notches, a support on which the button is pivoted and longitudinally adjustable, and a locking device

vice adapted to enter either of said notches 45 when the button has been longitudinally adjusted to the proper positions respectively and has been turned to the locking position.

6. In a locking device, a door member, a plate provided with two laterally turned 50 flanges resting against said member, a support extending between said member and said plate, and a turn-button pivoted to and longitudinally adjustable on said support and having a notch into which one of said 55 flanges is adapted to enter when the button is turned to a pre-determined position.

7. In a locking device, a door member, a plate provided with two laterally turned flanges resting against said member, a support extending between said member and said plate, and a turn-button pivoted to and longitudinally adjustable on said support and having two notches adapted to receive one of said flanges when the button is turned 60 to the locking position and has been longitudinally adjusted to the proper positions.

8. In a locking device, a turn button, a support upon which the button is pivoted and longitudinally adjustable, and locking 70 means which will permit the turn button to swing freely on its pivotal support, but which will engage with and lock the button against longitudinal movement, when the button has been moved to a pre-determined 75 position.

9. In a locking device, a turn button, a support upon which the button is pivoted and longitudinally adjustable, and locking 80 means which permits the button to swing freely on its pivotal support and which will engage with and lock the button against longitudinal movement from either of two positions, when the button has been moved to either of said two positions.

In testimony whereof I have signed my name to this specification.

ROBERT MORROW.
